PAGE 3

FIG. 5

FIG. 6

FIG. 1 is a perspective view of a typewriter embodying my new design;

FIG. 2 is another perspective view from a slightly different angle from that of FIG. 1, and with the platen cover in elevated position;

FIG. 3 is a top plan view of the typewriter shown in FIG. 1;

FIG. 4 is an elevational view of one side thereof;

FIG. 5 is a rear elevational view;

FIG. 6 is a bottom plan view;

FIG. 7 is an elevational view of the side opposite that of FIG. 4, and

FIG. 8 is a sectional view taken substantially along the line 8-8 of FIG. 3, showing the contour of the typewriter housing and certain related parts, certain of the keys being in elevation.

The essential features of my design reside in the portions shown in full lines on the drawings.

I claim:

The ornamental design for a typewriter, substantially as shown and described.
